United States Patent Office

Des. 178,809
Patented Sept. 18, 1956

178,809

SANDAL

Frank Santisi, Jamaica Plain, Mass.

Application April 12, 1956, Serial No. 41,035

Term of patent 14 years

(Ct. D7—7)

Fig. 1 is a top plan view of a sandal showing my new design;

Fig. 2 is a perspective view of the sandal shown in Fig. 1; and

Fig. 3 is a side elevational view showing the sandal of this invention from the side opposite to Fig. 2.

I claim:

The ornamental design for a sandal, as shown.
